Attnys.

UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

SEPARABLE FASTENER.

1,387,121.

Specification of Letters Patent. Patented Aug. 9, 1921.

Application filed January 16, 1920, Serial No. 351,792. Renewed April 23, 1921. Serial No. 463,907.

To all whom it may concern:

Be it known that I, FRED S. CARR, a citizen of the United States, and resident of Newton, in the county of Middlesex and 5 Commonwealth of Massachusetts, have invented an Improvement in Separable Fasteners, of which the following description, in connection with the accompanying drawings, is a specification, like characters on 10 the drawings representing like parts.

This invention pertains to improvements in separable fasteners. It is the object of 15 the invention to provide improved means for securing the sockets of snap fasteners to their carrying fabrics without the necessity of penetration of the goods, and without interference with the usual tubular projection which serves to locate the spring jaw or jaws of such sockets.

20 In the drawings, which show a preferred embodiment of one form of my invention:

Figure 1 is an elevation of two pieces of fabric secured together by the preferred form of fastener;

25 Fig. 2 is a section on the line 2—2 of Fig. 1;

Fig. 3 is a section on the line 3—3 of Fig. 2; and

Fig. 4 shows the socket and socket-attach- 30 ing part in the process of assembly.

Referring to the drawings and to the preferred form of my invention selected for 35 illustrative purposes, I have shown a stud 5, which may be secured to the stud-carrying fabric 6 in any suitable way typified by the expansion of the stud-securing plate 7 within the flanged-over stud base 8. I have also shown a socket including a casing 9 having flanged-over edges 10 and a central 40 tubular spring positioning projection 11 adapted to receive the head of the stud and slotted at the sides to receive resilient jaw means, herein typified by the two spring jaws 12, 12.

45 The preferred form of socket herein shown may be secured to the socket-carrying fabric 13 by expansible socket-securing means typified by the plate 14 having an

aperture 15 therethrough to surround the tubular projection 11 and adapted, when 50 squeezed into the socket with the socket-carrying fabric between the part 14 and the socket casing 9, to flatten out as best shown in Fig. 2, securing the fabric into the socket and firmly securing the socket to 55 the fabric.

It will be understood that I use the word "fabric" in its broader sense to include not only woven materials, but any flexible carrying medium.

While I have shown and described a preferred form of one embodiment of my invention, it will be understood that a number of changes involving omission, substitution, alteration and reversal of parts, and even 65 changes in the mode of operation, may be made without departing from the scope of my invention, which is best defined in the following claims.

Claims:

1. A socket for separable fasteners comprising, in combination, a dished spring-carrying plate having a tubular projection providing a stud-receiving recess, and securing means for fastening said spring-carrying plate to a fabric, said securing means proportioned to enter said dished spring-carrying plate and wedge the fabric therein, and having a hole therein through which 70 said tubular projection and the adjacent fabric may pass.

2. A socket for separable fasteners comprising, in combination, a dished spring-carrying plate having a tubular projection providing a stud-receiving recess, and securing means for fastening said spring-carrying plate to a fabric, said securing means proportioned to enter said dished spring-carrying plate and expand, thereby to wedge 85 the fabric therein, and having a hole therein 90 through which said tubular projection and the adjacent fabric may pass.

In testimony whereof, I have signed my name to this specification.

FRED S. CARR.
